UNITED STATES PATENT OFFICE.

GEORGE C. SCOTT, OF BOSTON, MASSACHUSETTS.

CHAIR-TIP.

SPECIFICATION forming part of Letters Patent No. 698,228, dated April 22, 1902.

Application filed July 8, 1901. Serial No. 67,483. (No model.)

To all whom it may concern:

Be it known that I, GEORGE C. SCOTT, a citizen of the United States, residing in Boston, in the county of Suffolk and State of Massachusetts, have invented certain new and useful Improvements in Chair-Tips, of which the following, taken in connection with the accompanying drawings, is a specification.

My invention relates to devices for preventing chairs and other articles of furniture from defacing finished floors and for diminishing the noise when moved from place to place.

Of the various kinds of chair-tips which have been put upon the market those having a facing of rubber are at this time most used; but rubber hardens with time, and thereby loses its resiliency, it wears away rapidly or else it disintegrates and is soon ruined by pieces breaking off, and it is also likely to become deformed, so that it does not cover the projection to which it has been attached or causes the piece of furniture to set insecurely or unevenly on the floor. To remedy these defects, I have devised a tip that protects the floor and also serves as a yielding buffer for the supports of the chair, the article, moreover, being made of materials that maintain their characteristic features and that are also cheap.

The invention consists in a resilient or yielding material forming a cushion and a facing of material suited to protect the cushion and the floor, together with a fastening passing through or about the cushion and facing to attach the device to the piece of furniture.

I have found by continued experiments that sole-leather will retain its shape, that it does not harden, has some cushioning effect, and is in all respects better adapted for a facing material for tips than any substance I have yet tried. As a substitute I sometimes use fiber of various kinds, which furnishes an efficient facing. Of the various substances which have suggested themselves to me for an intervening cushion or yielding medium the best results have followed the use of thick close felting, as this substance retains its properties without deterioration under the usual conditions of use. As a sub-

stitute good results follow the use of bulged spring-washers; but the best metal for this purpose is steel, and this rusts in time and may stain a finished floor.

The drawings show in Figure 1 a stool having my tips applied; Fig. 2, an enlarged section of a leg and a tip; Fig. 3, an enlarged section of a leg and a tip with a different facing; Fig. 4, an enlarged section of a leg and a tip with a different cushion.

In my preferred construction I form the facing *a* of my chair-tip of sole-leather, the outer edges being chamfered to prevent uneven wear and to present a finish. A hole *b* passes through the piece of leather and at the face thereof it is counterbored to receive the head of the nail *c*, which may rest against the seat *d* of the facing. The nail is passed through the hole *b* of the facing and driven into the leg *e* of the stool, and between the facing *a* and the end of the leg *e* I put a piece of thick felting to form the cushion *f*, the nail passing through a hole therein to hold it in place. The facing and the cushion may or may not be cemented to each other, my usual practice being not to secure the same together, as if each is free to move there is more opportunity of even wear of each part.

Sometimes instead of the piece of leather for the facing I use a piece of fiber *g*, and in such cases I put a washer *h* between the head of the nail *c* and the seat *d*, as the head of the nail may wear into the seat of the facing when made of such material. In place of material like felting for a cushion I sometimes use washers *i*, stamped from spring-metal and bulged outward, as cushions, and in such cases it is usual to put a bearing-plate *j* on the facing *a* and a similar plate *k* on the end of the support of the chair.

Having described my invention, I claim and desire to secure by Letters Patent of the United States—

1. A chair-tip comprising an apertured yielding washer engaging the lower end of the chair-leg, and an apertured facing-block counterbored on the under face thereof and engaging the washer, the aperture in the facing-block registering with that of the washer and having a nail passed through said registering apertures to engage in the chair-leg.

with the head of the nail received in said counterbored portion of the facing-block, substantially as described.

2. A chair-tip comprising outwardly-bulged apertured spring-washers, and an apertured facing-block, the washers being interposed between the chair-leg and the facing-block with means passing through the facing-block and washers and engaging in the chair-leg, substantially as described.

3. A chair-tip comprising outwardly-bulged apertured spring-washers and an apertured facing-block with the bulged portions of the

washers contacting with one another and having their opposite faces contacting with the facing-block and the chair-leg with means for securing the washers and facing-block to the chair-leg, substantially as described.

In testimony whereof I have hereunto subscribed my name this 5th day of July, A. D. 20 1901.

GEORGE C. SCOTT.
